UNITED STATES PATENT OFFICE.

JASON E. HARRIS, OF HOWARD, KANSAS.

INTAKE VALVE.

Application filed July 20, 1925. Serial No. 44,760.

This invention relates to intake valve mechanism for internal combustion engines of that type in which a series of cylinders are disposed to rotate around a stationary 5 crank shaft or in which a revolving crank shaft is disposed centrally between and in radial alinement with a series of stationary cylinders, and my object is to produce a construction in which there is an intake valve in 10 the head of each piston, and in which angular changes of relation between each cylinder and its piston connecting rod results in opening movement of the respective intake valve at the initial quarter of every alternate 15 revolution of the cylinders or shaft, and means for closing the valve on the ensuing quarter revolution, as the angularly related parts are resuming their initial or non-angular relation.

20 A further object is to provide means actuated by pressure produced by compression or explosive force between the head of the piston and cylinder, for preventing angular changes between the cylinder and connecting rod, from effecting the opening of the valve for the ensuing one and a fraction revolution, and means upon a suitable reduction of such pressure, for positioning the parts in their original relation so that at or 25 near the beginning of the next or third revolution, the ensuing change of angular relation between the piston and connecting rod shall again open the valve, this cycle of operations being similar for each cylinder and 30 its related valve mechanism, so that in a four cylinder four cycle engine, there shall be an average of two explosions for each revolution of the cylinders or crank shaft.

35 A still further object is to produce a mechanism of the character outlined, which is of simple, strong and relatively inexpensive construction, and in which carbon deposits upon the valve or its seat will tend to guard against rather than result in loss of pressure 40 and impairment of efficiency of operation of the engine.

With these objects in view the invention consists in certain novel and useful features of construction and combinations of parts 45 as hereinafter described and claimed; and in order that it may be fully understood reference is to be had to the accompanying drawings, in which:—

Figure 1 is a central vertical section of an 50 internal combustion engine embodying my invention, certain parts of the engine not

forming any part of the invention being omitted.

Figure 2 is an enlarged fragmental section of one of the cylinders disclosed by Figure 1.

Figure 3 is a section through the same cylinder but taken at right angles to the section disclosed by Figure 2, the section line being indicated by the dotted line III—III 65 of Figure 2.

Figure 4 is a cross section on the line IV—IV of Figure 3.

Figure 5 is a cross section on the line V—V of Figure 3.

Figure 6 is a cross section corresponding to Figure 5 but showing the valves open as distinguished from Figure 5 wherein said valves are shown as closed.

Figure 7 is a longitudinal section of the cylinder taken on the line VII—VII of Figure 6.

Referring to the drawings in detail, 1 indicates the customary or any preferred shaft suitably journaled in a frame or standard (not shown), and 2 is the crank of said shaft. 3 is the crank case of the engine and 4, 5, 6 and 7 indicate in this instance the cylinders of a four-cycle engine, provided at their outer ends with hemispherical heads or closures in order that the explosive forces shall be concentrated centrally upon the outer ends of the pistons 8, which being of like construction are identified by corresponding reference characters.

The pistons are provided at diametrically opposite sides with internal bearing hubs 9 for cross pins 10 connected centrally to the outer ends of the connecting rods 11 pivoted at their inner ends in any suitable manner on the shaft crank 2. As the cylinders are shown in the same vertical plane and it is desirable that the inner ends of the connecting rods shall be in the same plane, a special bearing 11^a is provided, which however, is capable of independent use and is therefore not detailed. The special construction and operation of said bearing forms the subject matter of a co-pending application.

Each connecting rod is provided at its outer end with a lug 12, and each piston with one or more, two in this instance, conical intake-valve seats 13 having ports 14, and engaging said seats for rotary action, are intake-valves 15 provided with central stems 16 projecting inwardly longitudinally of the respective pistons. The valves are

provided with diametric ports 16^a for registration at times with the respective ports 14, and springs 17 encircle and are secured to the stems and are anchored at their opposite 5 ends to the bearing lug 9 for the purpose of normally holding the valves substantially in the position shown by Figure 5, which is their closed position. Pivoted in bifurcation in the stem 16 of the valves are rocker 10 arms 18 having ball and socket connections 19 at their inner ends which permit of a limited rotary movement of the valves and also of pivotal movement of the rocker arms longitudinally of the piston for the purpose 15 of disposing the connected ends of said arms in the path of swinging movement of the lug 12 or beyond the range of movement of said lug, so that at times the latter may in changing its angular relation to the cylinder, 20 either engage said rocker arms and therefore turn the valves to open position against the opposition of spring 17, or pass said arms so as to avoid imparting opening movement to the valves.

25 Pivoted in a bifurcated lug 20 of the piston and standing in a plane radially thereof, is a forked lever 21, the fork of the lever receiving the inner ends of the rocker arms for the purpose of swinging them longitudinally of the piston, as hereinbefore explained. The outer end of the lever has a pin-and-slot connection at 23 with the stem 24 of a plunger 25 engaging a socket 26 formed in the head of the piston. An expansive coil spring 28 fits on the stem 24 and bears at its opposite ends against the lug 27 and the outer end of the lever and tends, when unresisted, to advance the plunger 25 and to thereby rock the lever and cause it to dispose the rocker arms in the 30 path of movement of the lug 12, a collar 29 on the inner ends of stem 24 being adapted to arrest the plunger movement by contact with the lug 27.

35 With the parts in the relative positions shown and the cylinders turning clockwise, and assuming that cylinder 4 is void of exhaust gases, it will be seen by reference to Figure 1, that as the plunger 25 is advanced because of the pressure of spring 28, the lever 21 has moved the interlocked ends of the rocker arms within the path of movement of the lug 12, which in the relative 40 change of angular position with respect to the cylinder as the latter moves eccentrically of the connecting rod, applies lateral pressure on said rocker arms and through them, effects rotary opening movement of the valves 15, from the position shown by Figure 5 to that shown by Figure 6, this valve movement starting when the cylinder is approximately above the crank shaft and ending when it has attained the position approximately shown by cylinder 5, of Figure 1, the 45 cylinder 4 and its piston connecting-rod, at-

taining their extreme angular relation as the valve attains its fully opened position. An explosive mixture supplied to the crank case in any suitable manner, passes into the combustion chamber of said cylinder through 70 the opened valves during this movement and during the ensuing quarter revolution of the cylinder, during which second quarter revolution the valves are closing under the power of springs 17, as at such time the angular 75 relation of the cylinder and connecting rod is diminishing, it being noted that the piston continues on its suction stroke from the time it leaves its initial position until it attains the approximate position occupied by cylinder 6.

As the cylinder starts on its third quarter revolution, the piston begins its advance or compression stroke, and as the pressure thus produced overcomes the power of spring 85 28, the plunger 25 recedes, and through lever 21, withdraws rocker arms 18 from the path of movement of the lug 12, as shown by reference to cylinder 7, so that the lug cannot 90 effect the reopening of said valves.

By the time cylinder 4 has attained approximately its original position as shown in Figure 1, the explosive mixture is fully compressed and the explosion occurs. The force of the explosion represses and retains 95 the plunger 25 retracted for a full half revolution or more, so that during such period of travel the rocker arms are out of the path of lug 12 and the changes of angular relation 100 between the cylinder and connecting rod 100 have no effect on the valves. Approximately at the beginning of the last half of the revolution induced by the explosion when the piston starts its scavenging stroke, the exhaust valve (not shown) opens and the pressure 105 in the combustion chamber dissipates rapidly, and shortly before the piston attains its initial position, the pressure is low enough to permit the spring 28 to readvance its plunger and thereby redispone the rocker 110 arms in the path of movement of lug 12, so that the latter, at the beginning of the third revolution, shall again engage the rocker arms and start the opening movement of the valves. It will thus be seen that in every 115 other revolution, of a four cylinder four-cycle engine of this character, the conventional two power strokes occur, and that the fresh mixture drawn through the pistons tends to prevent excessive heating thereof 120 and of the cylinders. It will also be apparent that the efficiency of an engine of this type cannot be impaired by loss of compression, as the rotary valves will utilize carbon 125 to maintain perfect fitting on their seats. The full power of the explosions is also secured as the arched heads of the cylinders centralize the force of the explosions on the pistons.

From the above description, it will be ap- 130

parent that I have produced a device which possesses all of the features of advantage pointed out as desirable, and while I have described and claimed the preferred embodiment of the same, I reserve the right to make all changes properly falling within the spirit and scope of the appended claims.

I claim:

1. The combination of a shaft having a crank, a crank-case inclosing the crank of the shaft, and a cylinder communicating at its inner end with the crank-case, a piston in the cylinder and a connecting rod between the piston and said crank, the piston having an intake port in its head, of a rotary valve carried by the piston head for controlling the port thereof and provided with a stem extending longitudinally of the piston, a rocker arm pivoted on said stem, means actuated by sufficient pressure in the combustion chamber of the cylinder to operate the rocker arm, and means actuated by a change of angular relation between the piston and the connecting rod, to apply lateral pressure on the rocker arm and effect rotation of the valve to open position.

2. The combination of a shaft having a crank, a crank-case inclosing the crank of the shaft, and a cylinder communicating at its inner end with the crank-case, a piston in the cylinder and a connecting rod between the piston and said crank, the piston having an intake port in its head, of a rotary valve carried by the piston head for controlling the port thereof and provided with a stem extending longitudinally of the piston, a rocker arm pivoted on said stem, means actuated by sufficient pressure in the combustion chamber of the cylinder to operate the rocker arm, means actuated by a change of angular relation between the piston and the connecting rod, to apply lateral pressure on the rocker arm and effect rotation of the valve to open position, and means to effect the reclosure of the valve.

3. The combination of a shaft having a crank, a crank-case inclosing the crank of the shaft, and a cylinder communicating at its inner end with the crank-case, a piston in

the cylinder and a connecting rod between the piston and said crank, the piston having a pair of intake ports of a pair of valves for controlling said ports, having parallel stems, rocker arms pivoted in said stems and having a ball and socket connection between the stems, a forked lever engaging the rocker arms, a plunger in the piston head, having a stem connected to operate said lever, a spring for advancing the plunger to cause the lever to move the connected ends of the rocker arms inwardly of the piston, and means actuated by the connecting rod to apply lateral pressure on the rocker arms to rotate the valves to open position.

4. The combination of a shaft having a crank, a crank-case inclosing the crank of the shaft, and a cylinder communicating at its inner end with the crank-case, a piston in the cylinder and a connecting rod between the piston and said crank, the piston having a pair of intake ports of a pair of valves for controlling said ports, having parallel stems, rocker arms pivoted in said stems and having a ball and socket connection between the stems, a forked lever engaging the rocker arms, a plunger in the piston head, having a stem connected to operate said lever, a spring for advancing the plunger to cause the lever to move the connected ends of the rocker arms inwardly of the piston, means actuated by the connecting rod to apply lateral pressure on the rocker arms to rotate the valves to open position, and means to close the valves when the lateral pressure is removed from said rocker arms.

5. The combination with the combustion chamber of an engine, of a piston and connecting rod, a valve in said piston, an operating connection for said valve whereby a pre-determined change in the angularity of the connecting rod shall effect operation of the valve, and control means affected by a pre-determined pressure in the combustion chamber for controlling the position of said valve operating connection.

In witness whereof I hereunto affix my signature:

JASON E. HARRIS.
